UNITED STATES PATENT OFFICE

EDMUND WEIGELE, OF BERGENFIELD, NEW JERSEY, ASSIGNOR TO G. & G. ATLAS SYSTEMS, INC., OF NEW YORK, N. Y., A CORPORATION OF NEW YORK

PNEUMATIC-DISPATCH-TUBE SYSTEM

Application filed December 9, 1924. Serial No. 754,698.

This invention relates to pneumatic dispatch tube systems, and particularly to such systems of the type known as "open systems". By the term "open systems" I mean systems in which each line is provided with an open end or bell mouth, into which carriers may be inserted directly and without the preliminary opening of a gate or valve, or, in other words, systems in which each line is normally open to the atmosphere at one end.

In these systems each line generally communicates at the delivery end with an exhauster of some suitable type so that when a carrier is inserted in the line it will be drawn through it by suction. Of course, if the full suction is maintained on the system at all times, whether there is any carrier to be transmitted or not, there will result a great waste of power.

The general object of the present invention is to provide a simple and efficient controlling device for such systems, which will reduce this waste of power to a minimum.

The more specific objects of my invention will appear more fully hereinafter.

In the accompanying drawings Fig. 1 illustrates a typical "open" tube system to which my invention is applied. Fig. 2 is a sectional view of the preferred form of my controlling device, with the valve in its normal "cracked" position. Fig. 3 is a fragmentary view of the valve of Fig. 2 showing the valve in its open or transit position.

Referring first to Fig. 1, 10, 11 represent the transit tube. In department stores and similar places where these systems are used extensively, the open end or bell mouth 12 is usually situated at the central cashier's station A, as is the delivery end 13 which is provided with a door 14, normally held closed as shown, by spring means. Intermediate the two ends 12 and 13 is located the salesman's station B where the line is provided with a carrier exit 15, normally closed by the spring pressed door 16, and with a carrier entrance 17, normally closed by a spring pressed door 18. Suction for conveying carriers through the transit tube 10, 11 is provided by an exhaust drum 19, or equivalent device, through the exhaust tube 20 which commu-

nicates with the transit tube 11 adjacent the delivery end 13.

The lay-out above described is well known. In operation, when a salesman at B desires to have change made, for example, he places the money and the sales slip in the usual cylindrical carrier and, opening the door 18, inserts the carrier into the tube 11. The suction applied adjacent the delivery end draws the carrier to that end of the system, where it pushes open the door 14, and drops out of the tube. The cashier then makes the necessary change in the contents of the carrier and places it into the tube 10 through the open end, or bell mouth 12. The doors 14, 16 and 18, being closed, the suction applied at the delivery end 13 is effective to draw the carrier through the tube 10, from which it emerges at the salesman's station B through the exit 15, pushing open the door 16 in a manner well understood.

It is evident that in a system of this character, unless some means are provided for preventing it, a large volume of air will constantly be sucked through the transit tubes, whether any carriers are being transmitted or not. This, of course, is very wasteful of power. Accordingly I have provided, between the exhauster 19 and the exhaust tube 20, a controlling device 21, which normally reduces the flow of air through the transit tubes to almost nothing, but which automatically applies full suction the moment a carrier is inserted into the transit tube. As soon as the carrier leaves the tube the suction is again cut down.

The construction and operation of this controlling device can best be understood from Figs. 2 and 3. This device includes a port 22 and a valve 23 for controlling that port. This valve, which may be of any suitable construction, such as those here shown, is connected by means of a valve stem 24 with a diaphragm 25. This diaphragm divides the casing in which it is mounted into two chambers, 26 at the left (as viewed in Fig. 2) and 27 at the right. The chamber 26 is maintained at atmospheric pressure through the opening 28, and the chamber 27 is normally maintained at the same pressure

as the exhaust tube 20 by the communicating passage 29. The normally closed valve 30 when opened admits the atmosphere to the chamber 27.

5 I shall now describe the way in which the valve 23 is opened automatically upon the insertion of a carrier into the tube.

With the valve in the almost-closed or "cracked" position illustrated in Fig. 2, but 10 a slight amount of air is drawn through the exhaust tube 20 and transit tubes 10, 11 by the exhauster. Since the transit tubes are 15 normally open to the atmosphere at the end 12 the pressure within those tubes and within the exhaust tube 20 is normally at substantially atmospheric pressure, the flow of air through the valved port 22 being insufficient to reduce the pressure materially. The spring 31 is of sufficient force to hold 20 the valve 23 in the position shown in Fig. 2 so long as the conditions just described exist in the tube system. However, as soon as a 25 carrier is inserted either into the open bell mouth 12 or into the entrance 17 of the transit tubes, the portions of the tubes in advance of the carrier are cut off from communication with the atmosphere, as, of course, is the exhaust tube 20. Immediately the small flow 30 of air through the "cracked" valve 23 establishes a partial vacuum in the portion of the system which has been cut off from communication with the atmosphere. And since 35 the chamber 27 at the right of the diaphragm 25 is in communication with that portion of the system, the pressure in that chamber is reduced, and as the result the atmospheric pressure in the chamber 26 pushes the diaphragm to the right and thus opens the valve 23. This, of course, establishes the full flow 40 of air through the system and transmits the carrier through the tube, from which it is delivered through the door 14 or the door 16, as the case may be.

Upon the delivery of the carrier there is, 45 of course, a rush of air through the port 22. This rush of air operates by its kinetic energy upon the vane 32 to which the valve 30 is connected and thus opens the valve 30 and admits the atmosphere to the chamber 27. The pressure in the chamber 27 is thus increased sufficiently so that the spring 31 is able to restore the valve 23 and the diaphragm 25 to their normal positions of Fig. 2.

I have found that with a device of the 50 character just described it is desirable to construct the valve 23 in such a way that the diaphragm 25 will not have to push the entire valve open against the current of air flow. In the drawings I have shown three forms 55 of valve designed with this purpose in mind. The first form is illustrated in Figs. 2 and 3, to which I have already referred generally. I shall now describe this valve in detail.

60 This valve of Figs. 2 and 3 includes a plu-

rality of separate disks or valve members, as, for example, the three which are marked 23^a, 23^b and 23^c. The largest disk 23^a is carried by a sleeve 33. Within this sleeve 33 is mounted the valve stem 24 which, at its inner 70 end, is tubular and near its outer end is provided with a shoulder 35 with which the intermediate disk 23^b is shown in contact in Fig. 3. The outer or smallest disk 23^c is adjustably secured to a reduced portion of 75 this valve stem, as indicated in Figs. 2 and 3. The inner tubular end of the valve stem 24 is secured to the center of the diaphragm 25 by means of bushings 36, or in any other suitable manner. Within this tubular portion of the valve stem 24 is located the 80 slideable rod 37 provided with ears 38 which pass through slots 39 in the tubular portion of the valve stem 24 and are adapted to contact with the sleeve 33, as indicated in Figs. 2 and 3.

The distance which the disk 23^a is to be spaced from the valve seat when no tube is in transit is determined by the adjusting screw 40, which is provided with a suitable lock nut 41. This screw contacts with the end of the rod 37 and thus limits the movement of that rod and of the sleeve 33 and the disk 23^a to the left.

When the diaphragm 25 is moved to the right in the manner above described upon the insertion of a carrier into the line, it does not move the entire valve 23 simultaneously, but first moves the valve stem 24 and the smallest disk 23^c which is secured to that stem. This, of course, results in the uncovering of the auxiliary port 42 in the intermediate disk 23^b and increases the flow of air through the port 22. As the movement of the diaphragm 25 and the stem 24 continues to the right, the shoulder 35 of the stem 24 lifts the intermediate disk 23^b from its seat against the largest disk 23^a and thus uncovers the auxiliary port 43 in the largest disk and further increases the flow through the port 22. Finally, upon the continued movement to the right of the diaphragm and the valve stem 24, the left hand margin of the slots 39 in that stem contact with the ears 38 of the rod 37, and in their further movement the diaphragm and stem therefore carry with them the sleeve 33 and disk 23^a. The result of this final movement is to open the port 22 completely and thereby establish a full flow of air through it. The extent to which the valve stem 24 may travel in opening the valve is determined by the adjusting screw 44, which has a lock nut 45.

From this description of the progressive opening of the several valve disks it is evident that the amount of force which would be required to open the entire valve 23 at one time against the air current is very materially reduced. Thus the device is rendered much more sensitive, and it operates more rapidly.

The closing of the three-part valve 23 upon the return of the diaphragm 25 involves merely a reversal of the operation above described. That is, the valve stem 24, which is drawn back by the diaphragm, first seats the smallest disk against the intermediate disk, then seats the intermediate disk against the largest disk, and finally brings the three disks together, back into the position of Fig. 2. Of course, it is not essential that the number of disks or valve members be three. There may be only two, or there may be more than three, depending upon the particular conditions encountered. Also, the normal leakage need not be between the first disk and the main port, but may be between another of the disks and the auxiliary port which it overlies.

Of course, many other types of valves may be used in place of that here shown, it being essential merely that the valve shall be so constructed that it may be opened quickly by the application of a comparatively slight force.

I am aware that it has heretofore been proposed to insert in the exhaust tube of a pneumatic dispatch system, or between the exhaust tube and exhauster, a controlling device adapted to operate automatically upon the insertion of a carrier into the tube for establishing the full flow of air through the tubes and to reduce the flow at times when no carrier is in transit. The Libby Patent No. 968,576, for example, suggests such a device, but the device shown in that patent is complicated in construction and indirect in its action.

By my invention here described I have provided an extremely simple and efficient control device for open vacuum systems by means of which the amount of power employed when no carrier is in transit is reduced to a negligible quantity and a great saving is thus effected. Also, by reason of the simple and direct controlling action, this device operates with great rapidity and thus makes possible the most efficient operation of the tube system as a whole.

The terms and expressions which I have employed are used as terms of description and not of limitation, and I have no intention, in the use of such terms and expressions, of excluding any mechanical equivalents of the features shown and described, or portions thereof, but recognize that various modifications are possible within the scope of the invention claimed.

What I claim is:

1. Power control apparatus for a pneumatic dispatch system of the vacuum minimum flow type comprising a transmission tube, a pneumatic exposed on one side to the air pressure in said tube, a stem connected to said pneumatic for movement thereby, a rod slidably mounted in the stem and provided

with a projection extending through a slot in said stem, and a valve for controlling carrier impelling air flow through the tube, said valve comprising an element operated directly by said stem, and an element operated by said stem through the medium of said rod. 70

2. Power control apparatus for a pneumatic dispatch system of the vacuum minimum flow type comprising a transmission tube, a pneumatic exposed on one side to the air pressure in said tube, a stem connected to said pneumatic for movement thereby and having a shouldered portion, a rod slidably mounted in said stem and provided with a projection extending through a slot in said stem, and a valve for controlling carrier impelling air flow through the tube, said valve comprising an element secured to said stem, an element operated by the shouldered portion of said stem, and an element operated indirectly by said stem through the medium of said rod. 75 80 85

3. Power control apparatus for a pneumatic dispatch system of the vacuum minimum flow type comprising a transmission tube, a pneumatic exposed on one side to the air pressure in said tube, a stem connected to said pneumatic for movement thereby and having a shouldered portion, a rod slidably mounted in said stem and provided with a projection extending through a slot in said stem, and a valve for controlling carrier impelling air flow through the tube, said valve comprising an element secured to said stem, an element operated by the shouldered portion of said stem, and an element having a sleeve connected thereto for operation by said stem through the projection on said rod. 90 95 100
